DISPOSABLE DIAPER

Evelyn H. Krusko, Newtown Square, Pa., assignor to Scott Paper Company, Delaware County, Pa.

Original design application Aug. 2, 1971, Ser. No.
168,529. Divided and this application Mar. 19,
1973, Ser. No. 342,605

Term of patent 14 years

Int. Cl. D24—04

U.S. Cl. D83—1 A

Fig. 1

Fig. 2

Fig. 3Fig. 4Fig. 5Fig. 6

FIG. 1 is a top plan view of a disposable diaper showing my new design, the pattern shown in FIG. 3 uniformly continuing over the entire top surface of the diaper;

FIG. 2 is a bottom view of the diaper shown in FIG. 1, the pattern shown in FIG. 3 uniformly continuing over the entire bottom surface of the diaper;

FIG. 3 is an enlarged portion of the design as indicated by 3—3 in FIG. 2;

FIG. 4 is an enlarged portion of the design as indicated by 4—4 in FIG. 1;

FIG. 5 is an enlarged portion of the design as indicated by 5—5 in FIG. 1; and

FIG. 6 is a side elevation view taken in the direction of 6—6 of FIG. 1.

This application is a division of U.S. design patent application Ser. No. 168,529, filed Aug. 2, 1971, and titled disposable diaper.

I claim:

The ornamental design for a disposable diaper, as shown and described.
